UNITED STATES PATENT OFFICE.

CARL HERMANN BEHNISCH, OF LUCKENWALDE, GERMANY.

MACHINE FOR CLEANING TEXTILE FIBERS.

No. 831,407.

Specification of Letters Patent.

Patented Sept. 18, 1906.

Application filed January 27, 1904. Serial No. 190,866.

To all whom it may concern:

Be it known that I, CARL HERMANN BEHNISCH, manufacturer, residing at Luckenwalde, in the Kingdom of Prussia, German Empire, have invented certain new and useful Improvements in Machines for Cleaning Textile Fibers, of which the following is a specification.

My invention relates to a feed device for machines for cleaning textile fibers, and more especially for machines designed to strip the fibers from agave-leaves. By means of the new device as many as from twelve to eighteen such leaves can be automatically 10 and simultaneously fed to the knife-drum and then returned from the same.

Referring to the accompanying drawings, Figure 1 is a side view of the improved device; Fig. 2, a plan of the same. Fig. 3 is an 20 enlarged representation of the right-hand upper portion of Fig. 1; and Fig. 4 is a plan of this portion, some parts being left away.

Bearings 1, carried by the frame 2, support the drum 4, which is furnished with a protective cap 3 and with knives 5, serving to remove the fibers from the leaves. Opposite to the drum 4 is located upon the frame 2 a pointed or hook-shaped elastic adjustable displacer 6, which serves for pressing the 25 fibers against the pointed ends of the knives. There are further lateral arms 8 and 9, supporting a shaft 10, carrying chain-wheels 11 and 12, rotated from a shaft 13 by means of a worm 14, worm-wheel 15, shaft 16, and 30 bevel-wheels 17 18; also, at the rear end of the frame 2 is a shaft 23, supported by arms 21 22 and carrying chain-wheels 19 20, said shaft being driven from the chain-wheels 11 and 12 by means of two chains 24 25 of equal 35 length. Connected with the chains 24 25 is an endless table consisting of wooden or iron bars 26 and being carried round by and with said chains.

Some of the links of the chains 24 25 are 40 furnished with pairs of upwardly-extending noses 28, provided with semicircular recesses 27, arranged one opposite to the other, said noses serving for the reception of a holder 31, having pivots 29 30. When rotating around 45 the chain-wheels, the noses 28 separate, Fig. 3, and afterward—that is to say, when the motion of the chains is again rectilineal—they regain their former position. In order to prevent the holder from leaving the chains at 50 that end of the machine where there are the

knives, circular guide-rails are provided upon which the pivots 29 30 glide.

To fix the agave-leaves A after being inserted into the holder 31, I prefer to employ an eccentric press 32', actuated in well-known manner by a lever system 34, operated by foot-pressure, the treadle, however, not being shown on the drawings. The jaws of the holder 31 being thus closed by the press, the thumb-screw 33 must be tightened to 60 hold them together. Instead of the press and thumb-screw any other suitable means may of course be employed.

The machine operates as follows: First the empty holder 31 is inserted into the press 32' 70 and then the agave-leaves are put into the holder. This latter is then closed by the foot being applied to the treadle. Thereupon the thumb-screw 33 is tightened. The holder, with the leaves, is now placed between 75 two of the opened or separated noses 28 and transported by them automatically toward the rotating knife-drum. First the pointed ends of the leaves and then the leaves themselves are operated by the knives, and after 80 that they are slowly withdrawn from the drum with and by the holder until they are finally taken out of the same.

Having described my invention, I claim as new—

1. In a machine for cleaning textile fibers, a knife-drum, a feed device, comprising parallel endless traveling chains located in front of the knife-drum and presenting pairs of jaws; means for supporting and for driving 90 the chains; an apron carried by the chains; and a fiber-holder gripped by the said jaws and carried along by the chains; substantially as described.

2. In a machine for cleaning textile fibers, 95 a knife-drum, a feed device, comprising parallel endless traveling chains located in front of the knife-drum and presenting pairs of jaws; means for supporting and for driving the chains; an apron carried by the chains; a 100 fiber-holding clamp gripped by the said jaws and carried along by the chains; and means for guiding the clamp; substantially as described.

In testimony whereof I have hereunto set 105 my hand in presence of two witnesses.

CARL HERMANN BEHNISCH.
